UNITED STATES PATENT OFFICE

EUGENE R. CAMPBELL, OF LA GRANGE, ILLINOIS, ASSIGNOR TO RAND McNALLY & COMPANY, OF CHICAGO, ILLINOIS, A CORPORATION OF ILLINOIS

DISPLAY-SHEET-SUPPORTING STRUCTURE

Application filed April 11, 1932. Serial No. 604,547.

My invention relates to structures for supporting display sheets such as maps and charts commonly used in educational institutions; and more particularly to such structures comprising a rack adapted to support thereon, preferably removably, frames on which the several display sheets are mounted, respectively, preferably on rollers.

My object is to provide a display-sheet-supporting structure of the character comprising a rack and frames for the display sheets, of such construction that by relative manipulation of the sheet-supporting frames a plurality of the display sheets, as selected by the user, may be exhibited at one time, disposed side-by-side, as for example for purposes of comparison one with the other, and preferably the frames separately removed from the rack for use at other locations as desired; and other objects as will be manifest from the following description.

Referring to the accompanying drawings:

Figure 1 is a view in front elevation of a display-sheet-supporting structure in accordance with my invention.

Figure 2 is an enlarged broken view in front elevation, of the structure of Fig. 1.

Figure 3 is an end view of the structure of Figs. 1 and 2.

Figure 4 is an enlarged section taken at the line 4 on Fig. 1 and viewed in the direction of the arrow; and

Figure 5, a front view of the structure of the preceding figures with an intermediate portion thereof broken away, showing the display sheets carried thereby in display position and relatively adjusted to exhibit them side-by-side.

Referring to the structure shown, it comprises a rack 6 formed of a vertical series of bars 7 forming supports and guides as hereinafter described, and crosspieces 8 connecting the bars 7 together adjacent their ends, the cross pieces 8 being shown as containing apertures 9 adapting the rack to be releasably secured to studs projecting from a wall, or the like.

The bars 7 which may be provided of any desirable number depending on the number of display sheets to be supported on the rack,

are each preferably of the cross-sectional shape shown throughout their length, thereby affording a flat rear portion 10 at which to secure the bar to the cross pieces 8, as by rivets 11; and forwardly projecting portions 12 and 13 vertically spaced apart with their forward edge portions curved rearwardly in an upward and a downward direction, respectively, as represented at 14 and 15, the rear terminal edges 16 and 17 of the portions 14 and 15 being forwardly spaced from the cross pieces 8 as shown.

The structure also comprises frames 18 and 19 on which the display sheets represented at 20 and 21 are respectively, mounted, the frames 18 and 19 each comprising a plate member 22 provided at its upper and lower edges with rearwardly extending flanges 23 and 24, respectively, shown as extending the full length of the frame. The upper flange 23 curves downwardly at its rear terminal edge as represented at 25 and the lower flange 24 curves upwardly at its rear terminal edge as represented at 26, the portions 25 and 26 being adapted to embrace the portions 14 and 15, respectively, of the rack and bear slidably against the portions 12 and 13 thereof when the frame is in position on the rack as shown.

Each frame also comprises forwardly extending brackets 27 secured to the ends of the plate 22 as by bolts 28, the brackets being shown as formed of a plate portion 29 having outwardly extending flanges 30, 31, 32 and 33 on its upper, rear, lower and front edges, the brackets being secured at their rear flanges 31 to the plate 22 by the bolts 28. The flanges 33 incline upwardly and forwardly and are provided with lips 34 at their upper extremities.

The brackets 27 of the frames are provided for supporting the spring rollers represented at 36 and on which the display sheets referred to are wound. These rollers may be of any suitable construction, as for example that commonly used in constructions of this general character, one end thereof having a journaling portion 37, as for example the left-hand end in Figs. 1 and 2, which is journaled in the plate portion 100

29 of the adjacent bracket 27 and the other end having a portion of angular shape in cross section which is connected with the spring of the roller and extends non-rotatably into a slot (not shown) of similar width in the plate 29 of the adjacent bracket 27, whereby upon pulling down on the free edge of the sheet the latter unwinds from the roller into the display position against 10 resiliency of the spring device on the roller.

In accordance with common practice the display sheets are provided along their free edges with a binding bar, or stiffening strip 38, the ends of the bars 38 extending beyond 15 the lateral edges of the sheets and into a position to engage the stop-lips 34 under the action of the springs of the rollers on which the display sheets are wound.

From the foregoing description it will be 20 understood that the frames are adapted to be selectively slid along the supporting bars 7 of the rack thereby permitting of the displaying of the selected sheets side-by-side as shown in Fig. 5; and by sliding them off 25 the ends of the bars at one end of the rack, they thus become detached from the rack for removal to the desired location for exhibition.

While I have illustrated and described a 30 particular construction embodying my invention, I do not wish to be understood as intending to limit it thereto as the same may be variously modified and altered without departing from the spirit of the invention.

35 What I claim as new, and desire to secure by Letters Patent, is:

1. A display-sheet-supporting structure comprising a plurality of substantially horizontally disposed parallel supporting members, and rigidly connected members for supporting both ends of sheets supported on said first-named members, said second-named members being relatively movable with the sheets in either direction lengthwise 40 of said first-named members into positions in which they extend on said first named members beyond the ends thereof, for the purpose set forth.

2. A display-sheet-supporting structure 50 comprising a plurality of substantially horizontally disposed parallel supporting members, and rigidly connected members for supporting both ends of sheets supported on said first-named members, said second-named

55 members being relatively movable with the sheets in either direction lengthwise of said first-named members into positions in which they extend on said first-named members beyond the ends thereof, said first-named members being adapted at ends thereof for the sliding therefrom of said second-named members.

3. A display-sheet-supporting structure 60 comprising a rack formed of substantially horizontally disposed parallel bars, means

connecting said bars together, said bars having forwardly extending portions terminating in upwardly extending flanges spaced forwardly of said means, display-sheet-supporting members comprising bars resting on, and slideable along, said first-named bars and having depending portions extending to the rear of said flanges and means carried by the second-named bars to support sheets to be displayed. 75

4. A display-sheet-supporting structure comprising a rack formed of substantially horizontally disposed parallel bars, means connecting said bars together, said bars having forwardly extending portions terminating in upwardly and downwardly extending flanges spaced forwardly of said means, display-sheet-supporting members comprising bars resting on, and slideable along, said first-named bars and having depending flanges and upwardly extending flanges extending to the rear of said first-named upwardly and downwardly extending flanges, respectively and means carried by the second-named bars to support sheets to be displayed. 80

5. A display-sheet-supporting structure comprising a rack formed of substantially horizontally disposed parallel bars substantially U-shaped in cross-section presenting cross members with vertically spaced upper 95 and lower forwardly extending portions with their forward edges extending upwardly and downwardly, respectively, means connected with said cross members for connecting said bars together, display-sheet-supporting members comprising bars resting on, and slideable along, said first-named bars and having depending flanges and upwardly extending flanges extending to the rear of the upwardly and downwardly extending portions, respectively, of said first-named bars and means carried by the second-named bars to support sheets to be displayed. 100

6. A display-sheet-supporting structure comprising a plurality of substantially horizontally disposed parallel supporting members, and display-sheet-supporting members supported on said first named members and each comprising portions supporting the ends of a sheet and a connecting portion, second named members being relatively movable with the sheets thereon in either direction lengthwise of said first named members from a central position thereon, for the purpose set forth. 110

7. A display-sheet-supporting structure comprising a plurality of substantially horizontally disposed parallel supporting members, display-sheet-supporting members supported on said first named members and relatively movable with the sheets thereon in either direction lengthwise of said first named members, said first named members being adapted for the sliding of said second named members beyond the ends thereof, 120

and means whereby said second named members are supported when extending partially beyond an end of said first named members.

8. A display-sheet-supporting structure comprising, in combination: a pair of bars; means to interconnect said bars for relative sliding movement longitudinally in either direction from a position of substantial registration of the ends thereof; means to attach one of said bars to a supporting surface; and means mounted on the remaining bar for support of each end of a sheet to be displayed.

9. A display-sheet-supporting structure comprising, in combination: a substantially horizontally disposed supporting member; a display-sheet supporting member supported on the first named member and relatively movable with the sheets thereon in either direction lengthwise of and to positions beyond either end thereof; and means whereby said second named member is supported when extending partially beyond either of said ends.

10. A display-sheet-supporting structure comprising, in combination: a plurality of parallel bars assembled for support in hori-

zontal position; a second bar mounted and slidable longitudinally upon each of said first named bars; the respective pairs of bars interconnected for support of the projecting portion of the second named bar of the pair when moved to a position to project beyond an end of the first named bar of the pair; roller-supporting brackets mounted upon each of the second named bars; and display-sheet-carrying rollers mounted in said brackets.

11. A display-sheet-supporting structure comprising a plurality of pairs of substantially horizontally disposed parallel supporting members; one member of each pair slidable upon the other thereof; means carried by each slidable member to support substantially the entire upper edge of a sheet to be displayed; sheets supported by said means normally hanging in superposed position with the outer thereof displayed to view; whereby a slidable member with its carried sheet may be displaced upon its associated member to uncover a sheet normally obscured to permit side by side inspection of two sheets.
